DESIGN FOR A WRIST WATCH BRACELET END

Rufus King, Plainville, Mass., assignor to Bugbee
& Niles Company, North Attleboro, Mass.

Application July 18, 1933. Serial No. 48,749

Term of patent 7 years

Be it known that I, RUFUS KING, residing in Plainville, in the county of Norfolk and State of Massachusetts, have invented a new, original, and ornamental Design for a Wrist Watch Bracelet End, of which the following is a specification, reference being had to the accompanying drawing, forming part thereof.

Figure 1 is an obverse view of a wrist watch bracelet end, showing my new design.

Figure 2 is a reverse view of the same, and Figure 3 is a section on line 3-3 of Figure 1.

I claim:

The ornamental design for a wrist watch bracelet end as shown.

In testimony whereof I have signed my name to this specification.

RUFUS KING.
